UNITED STATES PATENT OFFICE.

GEORGE EDWARD GOODING, OF BOSTON, MASSACHUSETTS, ASSIGNOR TO JOHN T. ROBINSON COMPANY, OF BOSTON, MASSACHUSETTS, A CORPORATION OF MASSACHUSETTS.

BOX-COVERING MACHINE.

Application filed October 1, 1923. Serial No. 665,783.

This invention relates to machines of the general type disclosed and claimed in Letters Patent No. 1,289,729, issued December 31, 1918, to Harrison S. Gipe. The machine shown in said patent is designed for the purpose of applying paper or other covering material to the tops and bottoms of boxes whose sides and ends have previously been provided with a covering of similar material.

10 The present invention has for its object to generally improve the covering applying and pressing devices of a machine of this type, and more particularly to provide means for smoothing down any rough portions at the corners of the box due to the imperfect application of the side and end covering, so as to cause the top and bottom covering to lie perfectly smooth and flat at these points; to provide improved means for 15 pressing the applied covering smoothly upon the box top or bottom, which pressing means is of such a character as to permit the same to adapt itself readily to inequalities in the work operated on; and to provide improved 20 means for controlling the operation of said pressing means so as to cause the same to engage the work at the proper time, said controlling means being adjustable to adapt 25 the same to boxes of different sizes.

30 The foregoing and other objects of the invention, together with means whereby the same may be carried into effect, will best be understood from the following description of one form or embodiment thereof 35 illustrated in the accompanying drawings. It will be understood, however, that the particular construction described and shown has been chosen for illustrative purposes merely, and that the invention, as defined by the 40 claims hereunto appended, may be otherwise practised without departure from the spirit and scope thereof.

In said drawings:

Fig. 1 is a simplified side elevation of 45 the machine with the adjacent side of the frame removed and certain of the parts, not essential to the invention herein claimed, omitted.

Fig. 2 is a detail sectional view taken substantially on the line 2-2, Fig. 1, illustrating the mounting of the pressing roller.

Figs. 3 and 4 are enlarged side elevations, illustrating the operation of the means for applying the covering material and smooth-

ing the same at the forward edge or corners 55 of the box.

Fig. 5 is a detail perspective view of one corner of the box, illustrating the improper position of the covering material prior to the operation of the smoothing means. 60

Fig. 6 is a section on the line 6-6, Fig. 3.

Fig. 7 is a detail side elevation of one of the heads which support the smoothing roller, the latter being shown in position 65 therein.

Except as hereinafter described, the machine herein shown, as to its general organization and the parts not illustrated, may, if desired, be substantially as more fully shown and described in Letters Patent No. 1,289,- 70 729, above referred to.

Said machine comprises a frame 25 provided with longitudinal ways in which is mounted for movement transverse to the covering applying and pressing devices, 75 herein after described, the carriage 26 of a work support 27 having a head 28 for supporting the box 3 to be covered. The upper part of the head 28 preferably comprises a board 4 detachably secured to said head, 80 whereby boards of different sizes may be provided for different sizes of boxes to be covered. The carriage 27 is reciprocated in its ways by mechanism which may be substantially similar to that shown in the Gipe 85 patent above referred to, but which is herein shown as of the type disclosed and claimed in another application, filed October 1, 1923, Serial No. 665,789. For the purpose of the present case, this mechanism may 90 be described as follows: The carriage 26 is formed at its under side with ears 30 connected by links 31 with levers 32 suitably fulcrumed, as at 33, to the frame 25. Disposed between the levers 32 is a lever 34 95 fulcrumed at 35 to a bracket 36 secured to said frame. The levers 32 and 34 are formed with longitudinal slots to receive slides 37 pivotally connected, as at 38, and longitudinally adjustable in said slots by means of mechanism generally indicated at 39 to adjust the operative connection of the levers 32 and 34 and thereby vary the length of the stroke of the carriage 26. The lever 34 is operated by a link 40 having a cam 100 roller 41 which cooperates with a cam 42 on a cam shaft 43 journaled in the frame 25, said link having a forked end 44 embrac-

ing said shaft, whereby said link is supported. The cam shaft 43 is connected by gearing 45 with a main shaft 46 suitably journaled in the machine frame and adapted to receive power from any suitable source through a belt pulley 47 thereon.

As in Letters Patent No. 1,289,729, the paper or other covering material 48 is supplied in the form of a continuous web from a suitable roll (not shown), is passed through suitable devices 49 for applying adhesive thereto, and is guided over supporting rollers 50 to its point of application to the box. Also, in accordance with the general principles explained in said prior Letters Patent, the end of the paper is applied to the box on the work support 27 when the latter is in the position shown in Fig. 1, by means of a roller 5, said work support being thereafter moved outwardly or toward the left, as shown in Fig. 1, drawing with it the end of the paper web. During the outward movement of the work support, said covering material is pressed down upon the box by means of a pressing device 52 which descends upon the box during the outward movement of the latter. Upon the completion of the outward movement of the work support, the web 48 is cut by means of a movable cutter 2 which cooperates with a fixed cutter 3 and which is carried by a swinging bail 55 pivoted to an auxiliary frame 66 supported by the main frame 25. The bail 55 is connected by links 56 with arms 57 on a rock shaft 58 journaled in suitable bearings in the main frame 25. One of said arms 57 forms part of a bell crank, the other arm 59 of which is provided with a cam roller 60 cooperating with a cam 62 on the cam shaft 43. This mechanism for operating the movable cutter is substantially similar to that covered by another application filed October 1, 1923, Serial No. 665,790, and is not claimed herein.

The applying roller 5 is journaled in a carrier comprising a pair of arms 63 connected by a cross rod 64 (Fig. 6) and loosely mounted on a rod 65 supported by the frame 66. The arms 63 are swung on the rod 65, to move the roller 5 from the position shown in Fig. 3 into that shown in Fig. 4 and apply the end of the covering material 48 to the box, by means of links 67 connected with arms 68 on a rock shaft 69 journaled in the frame 25. One of said arms 68 forms part of a bell crank, the other arm 70 of which is provided with a cam roller 71 cooperating with a cam 72 on the shaft 43.

From the foregoing it will be seen that the covering material 48 is applied by the roller 5 to the box at a point adjacent the forward end of the latter, or that end at the left in Figs. 1, 3 and 4, and that as the carriage 27 is moved transverse to the covering applying and pressing devices 5 and 52

toward the left in said figures, said devices will operate, in effect, to apply and press down said covering material upon said box progressively toward the inner or right end of the latter. The extreme forward or left end of said covering material is not smoothed down upon the box by this progressive movement of the applying and pressing devices, and it frequently happens, particularly when the edges of the covering material 73 (Figs. 3, 4 and 5), previously applied to the sides and ends of the box, have not been properly smoothed down, leaving wrinkles 730 at the corners, that the extreme forward edge of the covering material 48, particularly at said corners, will be curled upwardly, as indicated at 480 in Figs. 3 and 5, thereby resulting in imperfect work. In order to smooth down the covering material at these points, the following mechanism is provided.

Pivoted to coaxial pins 75 projecting laterally from the arms 63 is a pair of heads 76 each having secured thereto, by a bolt 77, a gib 78. The heads 76 and gibs 78 are so shaped as to provide, at the upper ends of said heads, open slots 79, and adjacent the lower ends of said heads, at the forward sides thereof, substantially closed slots 80. Retained by the gibs 78 in the slots 80 are the ends of a smoothing roller 8, the axis of said smoothing roller being consequently eccentric to the pivotal axis of the heads, and said roller being rotatable in said heads as well as bodily movable longitudinally of the slots 80. The ends of said roller are normally held in the lower ends of said slots, and upward bodily movement of said roller yieldingly resisted by springs 82 coiled about studs 83 projecting from said heads, said springs engaging at their opposite ends respectively the ends of the roller 8 and pins 84 carried by said heads. Slidably mounted in the slots 79 are blocks 85 pivoted to a tension frame comprising end members 86 pivotally mounted on the rod 64 and connected with one another by a cross bar 87. One of said end members 86 is provided with an arm 88 connected at its free end by a spring 89 with the adjacent arm 63 and pivoted at 90 intermediate its ends to a hanger 91 supported by a bracket 92 fixed to the upper frame 66. The hanger 91 is in the form of a threaded rod which passes loosely through an opening 94 in said bracket 92 and is provided above said bracket with a nut 95, whereby the vertical position of said hanger may be adjusted.

The operation of the mechanism last described is as follows: The heads 76 normally occupy the position shown in Fig. 3 with the smoothing roller 8 slightly below and in front of the applying roller 5, the exact position being determined by the adjustment of the hanger 91 by means of the nut 95. As

the arms 63 descend with the roller 5 to apply the material 48 to the box, as shown in Fig. 4, the eccentric mounting of the smoothing roller 8 with respect to the pivotal axis 75 of the heads 76 causes said roller, when pressed against the work, to turn said heads in a clockwise direction, thereby moving said roller outwardly or toward the left, and causing the same to smooth down the covering material at that edge of the box. This turning movement is yieldingly resisted by the spring 89 acting through the tension frame 86, the tension of the spring being increased by the downward movement of the 10 arms 63. The smoothing roller 8 is also pressed against the work by the spring 82 which yieldingly resists upward movement of said roller in the slots 80. Said roller 8 is therefore yieldingly pressed against the 15 work as it is moved outwardly thereover by the turning of the heads 76, thus flattening down the portions 730 and 430 of the covering material and making a neat joint at this edge of the box. The maximum tension exerted by the spring 89 through the tension 20 frame 86 upon the heads 76, as well as the normal position of the parts, is determined by the adjustment of the nut 95.

In accordance with the present invention, 25 the pressing member 52 comprises a roller, preferably provided with a rubber or similar peripheral surface, said roller being journaled at its ends in studs 100 slidably mounted in the ends of arms 101 fulcrumed 30 on the rod 65 and connected by a cross member 102 to form a pressing frame. Within the ends of the arms 101 are springs 103 acting to press the studs 100 outwardly and yieldingly resist their inward movement, the 35 movements of said studs being limited by lugs 104 secured, as by screws 105, to said arms and extending through openings therein into engagement with grooves formed in the studs. By means of this construction the 40 roller 52 is pressed yieldingly against the work, thereby providing for an even pressure upon boxes of different quality and compensating for variations in the thickness 45 of the boards 4.

50 The arms 101 are operated through links 106 by levers in the form of arms 107 on a rock shaft 108 journaled in the frame 25, said rock shaft having an arm 109 to which is connected a link 110 supported by a link 55 111 from the shaft 58 and carrying a cam roll 6 cooperating with a cam 113 on the shaft 43. One of the lever arms 107 is connected by a link 14 with a lever 15 fulcrumed at 16 on the frame 25 and formed with a 60 bearing surface 17 which is engaged by a roller 18 on a bracket 19 mounted in longitudinal ways 20 on the underside of the carriage 26 and adjustable in said ways longitudinally of said carriage by means of 65 an adjusting screw 21 connecting said car-

riage with an upwardly projecting lug 22 on the bracket.

The arms 101 and pressing roller 52 are raised through the connections described by the cam 113, which is formed with a low 70 portion 123 adapted, as the carriage 26 starts to move forwardly or toward the left in Fig. 1, to release the roller 6 and place the arms 101 and roller 52 under the influence of gravity. Said arms and roller, however, are at this time held elevated by engagement of the roller 18 with the bearing surface 17 of the lever 15 which acts through the link 14, lever 107, and link 106 to support said parts until the carriage 26, 80 in its traversing movement, carries the roller 18 out of engagement with said bearing surface 17, thereby releasing the pressing roller and permitting the same to engage the work. The exact time of engagement of 85 the roller 52 with the work may, therefore, be accurately determined by adjustment of the bracket 19, thereby adapting the machine for accurate operation upon boxes of 90 different sizes and shapes.

Having thus described my invention, I claim:

1. In a machine for covering the tops and bottoms of boxes, the combination with means for applying a sheet of covering material to a box bottom or top, of additional means for smoothing down the covering material at the corners of the box.

2. In a machine for covering the tops and bottoms of boxes, the combination with means operating toward one end of the box to apply a sheet of covering material to the bottom or top thereof, of means operating toward the opposite edge of the box for smoothing down the covering material adjacent said last named edge.

3. In a machine for covering the tops and bottoms of boxes, the combination with means including a roller for applying a sheet of covering material to a box bottom or top, of a separate roller for smoothing down the covering material adjacent an edge of the box.

4. In a machine for covering the tops and bottoms of boxes, the combination with means for applying a sheet of covering material to a box bottom or top and means for pressing said covering material upon the box, of additional means for smoothing down the covering material at the corners of the box.

5. In a machine for covering the tops and bottoms of boxes, in combination, means for continuously applying a sheet of covering material to a box bottom or top, a roller for pressing said sheet upon the box during the action of said applying means, and means for relatively moving said box and said applying means and roller.

6. In a machine for covering the tops and

- bottoms of boxes, the combination with means including a roller for applying a sheet of covering material to a box bottom or top and a roller for pressing the applied material upon the box, of a separate roller for smoothing down the covering material adjacent an edge of the box.
7. In a box covering machine, in combination, a work support, means for applying a sheet of covering material to a box on said work support, said work support and applying means being relatively movable toward and from each other, means for smoothing down the covering material adjacent an edge of said box, and means whereby said smoothing means is pressed upon said box and moved thereover when said applying means and work support are relatively moved toward one another.
- 10 8. In a box covering machine, in combination, a work support, a roller for applying a sheet of covering material to a box on said work support, a carrier for said roller, said carrier and work support being relatively movable toward and from each other, a roller for smoothing down the covering material adjacent an edge of said box, and means whereby said smoothing roller is pressed upon said box and moved thereover when said carrier and work support are relatively moved toward one another.
- 15 9. In a box covering machine, in combination, a work support, a roller for applying a sheet of covering material to a box on said work support, a carrier for said roller movable relative to said work support, and a roller for smoothing down the covering material adjacent an edge of said box, said smoothing roller being mounted on said carrier for bodily movement with respect thereto.
- 20 10. In a box covering machine, in combination, a work support, a roller for applying a sheet of covering material to a box on said work support, a carrier for said roller movable relative to said work support, a roller for smoothing down the covering material adjacent an edge of said box, and a carrier for said smoothing roller movably mounted on said first named carrier.
- 25 11. In a box covering machine, in combination, a work support, a roller for applying a sheet of covering material to a box on said work support, a second carrier pivotally mounted on said first named carrier, and a roller for smoothing down the covering material adjacent an edge of said box, said smoothing roller being mounted in said second carrier eccentric to the pivotal axis of the latter, and adjustable means, including a spring, connecting said carriers for yielding resisting pivotal movement of said second carrier.
- 30 12. In a box covering machine, in combination, a work support, means for applying a sheet of covering material to a box on said work support, a carrier for said applying means movable relative to said work support, a second carrier pivotally mounted on said first named carrier, a roller for smoothing down the covering material adjacent an edge of said box, said smoothing roller being mounted in said second carrier eccentric to the pivotal axis of the latter, a pivoted tension frame having means engaging the slots in said heads, and
- work support, said work support and applying means being relatively movable toward and from each other and transversely to apply the covering, means for smoothing down the covering material adjacent an edge of said box, and means whereby said smoothing means is pressed upon said box and moved transversely thereover in a direction opposite to the relative transverse covering applying movement of said work support and applying means when said work support and applying means are relatively moved toward one another.
- 35 13. In a box covering machine, in combination, a work support, means for applying a sheet of covering material to a box on said work support, a carrier for said applying means movable relative to said work support, means mounted on said carrier and movable over said box when said carrier is moved toward said work support for smoothing down the covering material adjacent an edge of said box, and means rendered operative by movement of said carrier toward said work support for applying pressure to said smoothing means.
- 40 14. In a box covering machine, in combination, a work support, means for applying a sheet of covering material to a box on said work support, a carrier for said applying means movable relative to said work support, a second carrier pivotally mounted on said first named carrier, a roller for smoothing down the covering material adjacent an edge of said box, said smoothing roller being mounted in said second carrier eccentric to the pivotal axis of the latter, and means, including a spring, connecting said carrier for yielding resisting pivotal movement of said second carrier.
- 45 15. In a box covering machine, in combination, a work support, means for applying a sheet of covering material to a box on said work support, a carrier for said applying means movable relative to said work support, a second carrier pivotally mounted on said first named carrier, a roller for smoothing down the covering material adjacent an edge of said box, said smoothing roller being mounted in said second carrier eccentric to the pivotal axis of the latter, and adjustable means, including a spring, connecting said carriers for yielding resisting pivotal movement of said second carrier.
- 50 16. In a box covering machine, in combination, a work support, a roller for applying a sheet of covering material to a box on said work support, a carrier for said roller movable relative to said work support, a pair of slotted heads coaxially pivoted on said carrier, a smoothing roller mounted in said heads eccentric to the pivotal axis of the latter, a pivoted tension frame having means engaging the slots in said heads, and

a spring connecting said tension frame and carrier.

17. In a box covering machine, in combination, a work support, a roller for applying a sheet of covering material to a box on said work support, a carrier for said roller movable relative to said work support, a pair of slotted heads coaxially pivoted on said carrier, a smoothing roller mounted in said heads eccentric to the pivotal axis of the latter, a pivoted tension frame having means engaging the slots in said heads, an adjustable hanger for said tension frame, and a spring connecting said tension frame and carrier.

18. In a box covering machine, in combination, a work support, means, including a carrier movable relative to said work support, for applying a sheet of covering material to a box on said work support, a second carrier movably mounted on said first named carrier, a smoothing roller rotatable and bodily movable in said second carrier, and a spring for yieldingly resisting bodily movement of said roller.

19. In a box covering machine, in combination, a work support, a roller for applying a sheet of covering material to a box on said work support, a carrier for said roller movable relative to said work support, a second carrier pivotally mounted on said first named carrier; a smoothing roller rotatable and bodily movable in said second carrier eccentric to the pivotal axis of the latter, and a spring for yieldingly resisting bodily movement of said smoothing roller.

20. In a box covering machine, in combination, a work support, a roller for applying a sheet of covering material to a box on said work support, a carrier for said roller, said carrier and work support being relatively movable toward and from each other and transversely to cause said roller to apply the covering, a second carrier pivotally mounted on said first named carrier, a smoothing roller rotatable and bodily movable in said second carrier eccentric to the pivotal axis of the latter, means, including a spring, connecting said carriers for yieldingly resisting pivotal movement of said second carrier, and a spring for yieldingly resisting bodily movement of said smoothing roller in said second carrier.

21. In a box covering machine, in combination, a work support, means for applying a sheet of covering material to a box on said work support, a roller for pressing said covering material upon said box, means for yieldingly pressing said roller against said box, and means for relatively moving said work support and roller.

22. In a box covering machine, in combination, a work support, means for applying a sheet of covering material to a box on said

work support, means for smoothing down said covering material at an edge of said box, a roller for pressing said covering material upon said box, means for yieldingly pressing said roller against said box, and means for relatively moving said work support and roller.

23. In a box covering machine, the combination with a work support, of means for pressing a sheet of covering material upon a box on said work support comprising a roller, a pair of swinging arms, means for moving said arms toward and from said work support, bearings for said roller mounted in said arms for a limited movement relative thereto, and spring for yieldingly resisting such movement.

24. In a box covering machine, the combination of a work support and means for pressing a sheet of covering material upon a box thereon, said work support and pressing means being relatively movable transversely and toward and from one another, and adjustable means controlled by the relative transverse position of said parts for controlling their relative movement toward and from one another.

25. In a box covering machine, in combination, a work support, means movable toward said work support for pressing a sheet of covering material upon a box thereon, means for relatively moving said pressing means and work support transversely, and means including a part carried by said work support and adjustable thereon for preventing movement of said pressing means toward said work support.

26. In a box covering machine, in combination, a work support, means movable toward said work support for pressing a sheet of covering material upon a box thereon, means for moving said work support transversely, means for operating said pressing means, and a lever cooperating with said work support, controlled by the transverse position thereof, and connected with said operating means for holding said pressing means against movement toward said work support.

27. In a box covering machine, in combination, a work support, means for reciprocating the same, a pressing roller, an oscillating frame by which said roller is carried, a lever for oscillating said frame, means for operating said lever, a second lever connected with said first named lever and having a bearing portion, and a bracket adjustably secured to said work support and adapted to engage said bearing portion to hold said levers against operation when said work support is in one position.

In testimony whereof I affix my signature.

GEORGE EDWARD GOODING.
